UNITED STATES PATENT OFFICE.

WILLIAM PEARSALL, OF WORCESTER, MASSACHUSETTS, ASSIGNOR TO
MATTHEW J. WHITTALL, OF WORCESTER, MASSACHUSETTS.

NEEDLE-LOOM.

No. 839,315.

Specification of Letters Patent.

Patented Dec. 25, 1906.

Application filed February 23, 1904. Serial No. 194,708.

To all whom it may concern:

Be it known that I, WILLIAM PEARSALL, a subject of the King of England, residing at Worcester, in the county of Worcester and State of Massachusetts, have invented a new and useful Needle-Loom, of which the following is a specification.

This invention relates to that class of looms in which the filling or weft threads are carried across the loom by a long bar or needle.

The especial objects of this invention are to provide a simple, efficient, and reliable needle-motion for looms and to combine the needle-motion with simple and efficient tension and take-up devices, together with a simple and efficient selvage-motion, which will finish one edge of the fabric without crimping or puckering.

To these ends this invention consists of the needle-loom and of the combinations of parts therein, as hereinafter described, and more particularly pointed out in the claims at the end of this specification.

In the accompanying two sheets of drawings, Figure 1 is a front view of sufficient parts of a loom to illustrate the connections for operating the needle. Fig. 2 is a detail view of the take-up arm. Fig. 3 is a detail plan view of the carriage for operating the needle. Fig. 4 is a detail view of the skewer or pin which holds a loop of the filling-thread while the needle is being retracted. Fig. 5 is a plan view of sufficient parts of the loom to illustrate the selvage motion; and Figs. 6 to 8, inclusive, are diagrammatic views illustrating different positions of the parts in the formation of the selvage.

The needle-loom covered by this application for patent is designed for weaving the chain or body portion of a pile fabric, this form of loom having been especially designed for use in connection with the tufting mechanism shown, described, and claimed in a separate application for patent which has been executed by me on even date herewith.

Referring to the accompanying drawings for a detail description of the construction, as shown in Fig. 1 at one side of the loom is a framework comprising side frames A, connected by an upper tie-beam B and a lower tie-beam C. Carried by the framework is a slideway 10, movably mounted on which is the carriage 11, which carries a needle N,

which moves back and forth through a guide 55 G to carry a loop of filling-thread across the loom. The needle-carriage 11 is connected by a link 12 to an operating-lever L, which is connected to be oscillated by a link 13 from a crank-arm 14, carried by the shaft 15. By 60 means of this construction the needle will be moved back and forth in a horizontal line across the loom. The filling or weft thread may be drawn from a coil or other suitable source of supply S and passes through a tension-clamp T. From the tension-clamp T the thread passes around a small guide-roller 16, carried by the take-up arm 17, and through a guide or eye in the upper end of the take-up arm 17. As shown most clearly in Fig. 2, 70 the take-up arm 17 is normally moved back by a spring to draw back the surplus length of filling-thread which is carried across the loom to form a loop in weaving the selvage at the opposite side of the fabric. The take-up 75 arm 17 is guided near its upper end by suitable curved guides 18. From the thread guide or eye at the upper end of the take-up arm the thread passes through a feeler F, controlling any of the ordinary weft stop-motions, and thence passes through an eye or guide near the point of the needle.

The selvage-motion at the opposite side of the loom is most clearly illustrated in the second sheet of drawings. As shown in Fig. 85 5, 19 designates a bracket extending from the framework of the loom, and carried by the bracket 19 is a curved raceway 20, which supports a shuttle 21. The shuttle 21 is provided at its rear end with a projection or 90 point 22 for engaging the loop of thread which is carried across the loom and while it is held in place by the needle N. The shuttle 21 is vibrated back and forth in its curved or arc-shaped path by means of the shuttle 95 guide or fork 23, which is operated by a link 24. Coöoperating with the shuttle and needle is a skewer or pin 25, which is mounted in a guide 26 and receives the loop of thread to prevent the tension of the take-up arm 100 and draft of the needle on its return stroke from puckering or straining the selvage edge of the fabric. The skewer or pin 25, as most clearly illustrated in Fig. 4, is pivoted at its rear end to a lever 27. The lever 27 is moved forward by a spring 29 and is moved back by a cam 28.

The operation of the parts in forming a

selvage according to this invention is most clearly illustrated in Figs. 6 to 8, inclusive. As shown in Fig. 6, the point 22 of the shuttle 21 first passes through the loop of filling-thread while the same is held in place by the needle N. Simultaneously with the passage of the shuttle through this loop the needle N commences its return stroke and the skewer or pin 25 is moved forward through the loop, as shown in Fig. 7. When the shuttle has passed completely through the loop, as shown in Fig. 8, the take-up arm 17 and the return draft of the needle N will draw the loop tight around the skewer or pin 25 and the skewer or pin 25 will support the loop of filling-thread and properly guide the same into place, when the fabric is beaten up by a vibrating lay in the ordinary manner.

When a needle-loom as thus constructed is employed for weaving the chain of a tufted or pile fabric, the successively-formed piles may be held back out of the way by the supporting-wire W, (shown in Figs. 5 to 8, inclusive;) but it is to be understood that the supporting-wire W and the connections for operating the same form no part of the subject-matter claimed in this application for patent, as I have specifically claimed these features in my companion application for patent before referred to.

I am aware that numerous changes may be made in practicing this invention by those who are skilled in the art without departing from the scope thereof as expressed in the claims. I do not wish, therefore, to be limited to the construction I have herein shown and described; but

What I do claim, and desire to secure by Letters Patent of the United States, is—

40 1. In a needle-loom, the combination of the weft-needle, means coöperating therewith to form a selvage, a take-up mechanism for pulling back the surplus thread carried across by the weft-needle, and means mounted on the loom-frame and movable parallel with the warp for preventing the tension of

the take-up mechanism from acting on the selvage.

2. In a needle-loom, the combination of a weft - needle, means coöperating therewith to form a selvage, a take-up mechanism for drawing back surplus thread carried across by the weft-needle, a skewer or pin mounted in the loom-frame and movable parallel with the warp, and means for operating said skewer to engage the weft-thread and prevent the tension of the take-up mechanism from acting on the selvage.

3. In a needle-loom, the combination of the weft-needle, means coöperating therewith to form a selvage, a take-up mechanism for pulling back surplus thread carried across by the weft-needle, a skewer or pin mounted in the loom-frame and movable transversely with respect to the weft-needle, a spring for moving the skewer forward to engage a loop of weft-thread to prevent the take-up mechanism acting on the selvage, and a cam for moving the skewer back out of the way for the next succeeding pick.

4. In a needle-loom, the combination of a weft-needle, a shuttle, a curved or arc-shaped runway for the shuttle, a fork pivoted upon a vertical axis and operating the shuttle to coöperate with the weft-needle to form a selvage, a tension - clamp through which the weft-thread is drawn, a swinging spring-pressed arm forming a take-up mechanism for drawing back surplus thread carried over by the weft-needle, a skewer or pin movable transversely with respect to the weft-needle, and a cam for operating the skewer to engage the loop of weft-thread to prevent the tension of the swinging spring-pressed arm from acting upon the edge of the fabric.

In testimony whereof I have hereunto set my hand in the presence of two subscribing witnesses.

WILLIAM PEARSALL.
